CONTROL SYSTEM FOR AN AUTOMATIC DISHWASHER

Donald S. Cushing, Louisville, Ky., assignor to General Electric Company, a corporation of New York
Filed Mar. 24, 1967, Ser. No. 625,680
Int. Cl. F04d 15/02, 13/08; B08b 3/02
U.S. Cl. 134—57 9 Claims

ABSTRACT OF THE DISCLOSURE

A system employing a pressure sensitive fill switch to de-energize a water valve and energize a timer motor and motor-driven pump. Drain solenoid on pump is controlled by timer switch. Flood switch ameliorates malfunction of either water valve or fill switch by de-energizing water valve and allowing energization of drain solenoid.

Background of the invention

This invention relates generally to automatic dishwashers and, more specifically, to an improved and simplified control system for an automatic dishwasher.

The operation of a typical automatic dishwasher for use in the home involves several separate fills or charges of water, agitation or recirculation of each charge of water within the wash chamber to effectuate a wash or rinse action therein, and drainage of each charge. This provides, generally, one or more pre-rinses, a wash, and one or more post-rinses. The last post-rinse is normally followed by a drying period wherein the dishes are heated by an electrical heating element to facilitate their drying. Additional rinses or washers may be added to the foregoing typical operational cycle.

Of course, control means must be provided to sequentially energize and de-energize the various components of the dishwasher to carry out the cycle. Usually, a sequence control means having a timer motor and several cam-operated switches is provided with each switch controlling one of the components. Although such control means has proven successful and is in general use today it is a relatively expensive component of the dishwasher, due in part to the large number of cams and switches involved. Additionally, of course, the greater number of switches and cams which are involved increases the complexity of the device and thus increases the likelihood of need for service.

The amount of water in each charge admitted to the wash chamber must be maintained within certain limits to assure, on the one hand, that adequate water is present to effectuate suitable wash or rinse action and, on the other hand, to avoid overflow or flooding which may result if an excessive amount of water is admitted. Most dishwashers manufactured today provide a timed fill. That is, the sequence control means maintains the water valve open for a predetermined length of time which is calculated to provide a given amount of water within the aforementioned limits. This requires a relatively accurate, and thus expensive, timer motor. Similarly, the draining of the wash chamber is generally time controlled which requires an accurate timer motor to assure complete drainage or, in the alternative, requires a margin of safety in the form of excessive drain time which creates undesirable noise as the drain pump continues to run after the wash chamber is drained and which also tends to elongate the time of the overall operational cycle of the dishwasher.

As will become evident as this description proceeds, the present invention provides an improved control system for an automatic dishwasher which is greatly simplified in

2

comparison to heretofore available controls but which provides all the functions of the more complex systems. Moreover, the control system of the present invention allows use of a less accurate timer motor since fill and drainage of the wash chamber are not subject to the timed accuracy of the sequence control means. Additionally, overflow protection is provided.

Summary of the invention

This invention is related to an automatic dishwasher having a wash chamber, a motor-driven pump having a housing, an electrically-operated valve to control the flow from the pump and having a wash position and a drain position, and an electrically-operated means to admit water to the wash chamber. Specifically, this invention provides an improved control system comprising a pressure sensitive fill switch having first and second operative positions and located to sense the pressure within the pump housing. A sequence control means including a timer motor and at least one switch having at least one closed position and operated in predetermined sequence by the timer motor is also provided. The means to admit water is electrically connected to the fill switch to be energized whenever the fill switch is in its first operative position. The timer motor and the motor-driven pump are electrically connected to the fill switch to be energized whenever the fill switch is in its second operative position. The electrically-operated valve is connected to the fill switch and to the switch in the sequence control means whereby the electrically-operated valve is moved toward its drain position whenever the fill switch is in its second operative position and the switch in the sequence control means is in its closed position.

In a specific embodiment of the present invention, a level sensitive flood switch is positioned to operate as the liquid level within the wash chamber exceeds a predetermined height. The flood switch is in electrical series circuit with the means to admit water to override the fill switch and de-energize the means to admit water whenever the liquid level exceeds the predetermined height.

Brief description of the drawings

While the specification concludes with claims particularly pointing out and distinctly claiming the subject matter which is regarded as the invention, it is believed that the invention will be better understood from the following description of the preferred embodiments taken in connection with the accompanying drawings, in which:

FIGURE 1 is an elevational view, partially cut away to show details, of an automatic dishwasher employing the present invention;

FIGURE 2 is an enlarged detail view of a pump and a valve employed in the dishwasher of FIGURE 1;

FIGURE 3 is a fragmentary view of the pump of FIGURE 2 viewed from the side opposite that of FIGURE 2;

FIGURE 4 is a schematic representation of the electrical circuitry of the control system of the present invention;

FIGURE 5 is a schematic representation of the action of the timer controlled switches in the circuitry of FIGURE 4; and

FIGURE 6 is a schematic representation similar to that of FIGURE 4 but showing a modification thereof.

Description of the preferred embodiments

Referring now to the drawings, and particularly to FIGURE 1 thereof, there is illustrated an automatic dishwasher 10 having an outer cabinet 11 defining therein a wash chamber 12. Disposed within wash chamber 12 are dish-supporting racks 13 and 14 which are adapted to receive and support dishes or other articles to be washed within wash chamber 12. A door 15 is provided in one

wall of cabinet 11, pivotal about a hinge means 16, a to provide access to wash chamber 12. When door 15 is pivoted downwardly, rack 13 can be at least partially withdrawn from wash chamber 12 by means of a slide and roller system 17 provided at each side of rack 13 and slidably supporting rack 13 from the inner wall of cabinet 11. Similarly, rack 14 can be at least partially withdrawn from wash chamber 12 by means of a roller 18 which rides upon a track 19 provided at each side of cabinet 11.

The lower extremity of wash chamber 12 is defined by a bottom wall 20 which gradually slopes to a low point 21 near the center of the dishwasher. Disposed below the low point 21 is a sump 22 which may be formed integrally with the bottom wall 20 or which may be a separate element secured thereto. Projecting upwardly from bottom wall 20 near the center of wash chamber 12 is a pedestal 23 which rotatably supports a reaction-type spray device 24. Spray device 24 as a plurality of orifices 25 through which wash fluid is ejected to effectuate a wash action upon articles supported by rack 13 and 14. At least one of the orifices 25 is directed such that the reaction force created by wash fluid passing therethrough causes rotation of spray device 24 about a substantially vertical axis.

Wash fluid is propelled into spray device 24 by a pump 26 which is driven by an electric motor 27. Pump 26 and motor 27 are secured together to form a motor-pump assembly which is suitably supported from bottom wall 20. A flexible boot or conduit 28 interconnects sumps 22 with the inlet of pump 26. Boot 28 is secured to sump 22 by means of a clamp 29 and is similarly secured to pump 26 by means of a clamp 30.

Referring now to FIGURES 2 and 3, it can be seen that pump 26 has a housing 31 defining an inlet 32 which receives fluid from boot 28. Disposed within housing 31 is an impeller (not shown) mounted for rotation to pump fluid through housing 31 and driven by motor 27. A first outlet 33 interconnects pump 26 with spray device 24 while a second outlet 34 interconnects pump 26 with a normal household sewer system (not shown). Referring again briefly to FIGURE 1, it can be seen that outlet 33 is connected to a flexible conduit 35 by means of a clamp 36. Conduit 35 extends up through pedestal 23 to a fitting 37 upon which spray device 24 is rotatably mounted, it being understood that fitting 37 is secured to pedestal 23. Referring again to FIGURES 2 and 3, water, or other liquid, entering pump 26 through inlet 32 will be pumped either into spray device 24 through outlet 33 or discharged from dishwasher 10 through outlet 34.

An outlet valve mechanism 38 is provided to selectively control through which of the outlets 33 or 34 the fluid will egress from pump 26. Outlet valve mechanism 38 includes a frame 39 suitably secured to pump housing 31. Frame 39 carries a solenoid 40 having electrical terminals 41 and 42 and an armature 43. Armature 43 is adapted to be drawn into solenoid 40 to the position illustrated in FIG. 3 when solenoid 40 is energized by the presence of electrical energy across terminals 41 and 42. Armature 43 has attached thereto a link 44 which extends out from armature 43 and then laterally through a slot 45 in frame 39. Link 44 is provided with a washer 46 rigidly secured thereto to prevent link 44 from escaping from slot 45. Link 44 also passes through a slot 47 in a plate 48. Plate 48 is carried by arm 49 which is pivotally carried by pump housing 31 and extends into pump housing 31. Within pump housing 31, arm 49 has a substantially 90° bend and supports within pump housing 31 valve elements 50 and 51. Valve element 50 is adapted to seal off outlet 33, and thus direct fluid from pump 26 out through outlet 34, when outlet valve mechanism 38 is in one condition of operation (shown in dotted lines in FIGURE 2). Valve element 51 is adapted to seal off outlet 34, and thus direct fluid from pump 26 out through outlet 33, when valve mechanism 38 is in the other condition of operation (also shown in dotted lines in FIGURE 2).

A spring 51a is secured at one end to frame 39 and at

its other end to plate 48 to normally urge plate 48 to rotate in a direction whereby valve element 51 seals off outlet 34. When solenoid 40 is energized, it overcomes the force of spring 51a to move valve element 50 toward sealing engagement with outlet 33. As can be seen from a review of FIGURES 2 and 3, when armature 43 is fully drawn into solenoid 40, plate 48 and arm 49 assume the positions shown in solid lines in FIGURES 2 and 3. Thus, when solenoid 40 is energized, valve element 50 is moved only part way toward sealing engagement with outlet 33; however, when pump 26 is operating and fluid is passing therethrough, the pressure of the fluid will move arm 49 and valve element 50 to the position wherein element 50 seals off outlet 33. The fluid pressure will maintain valve element 50 in sealing relationship with outlet 33 until substantially all of the fluid has been pumped out through outlet 34 whereupon the pressure within housing 31 will drop and spring 51a will move arm 49 to the position wherein outlet 33 is opened and outlet 34 is closed. Slot 47 is elongated to allow arm 49 and plate 48 to pivot in response to the fluid pressure to the position wherein valve element 50 seals off outlet 33 even though link 44 remains stationary.

The outlet valve mechanism 38, including arm 49 and valve elements 50 and 51 is described in greater detail, along with other refinements thereof, in application Ser. No. 549,675, filed May 12, 1966 by Thomas E. Jenkins, now Patent No. 3,367,368, issued Feb. 6, 1968, and assigned to the General Electric Company, assignee of the present invention. This application does not claim as new the outlet valve mechanism per se.

An electrical heating means 52 is supported in spaced relationship from bottom wall 20 and may be employed to heat the wash fluid in wash chamber 12, although not so adapted in this application, and to facilitate drying of articles supported by racks 13 and 14 upon completion of the wash and rinse operations. Means, in the form of an electrically-operated valve 53, are provided to control the admission of water, or other fluids, to wash chamber 12. Valve 53 is connected at one side to a conduit 54 which communicates with the normal household plumbing system and, at the other side, is connected to a conduit 55 which communicates with wash chamber 12 through an inlet funnel 56. A sequence control means 57, having a manually operable knob 58, is conveniently positioned on door 15. Sequence control means 57 is disposed within door 15 and knob 58 projects out through the front wall thereof to be conveniently manipulated by the operator of the dishwasher 10.

Referring now to FIGURE 4, the control system of the present invention is illustrated in schematic form. As can be seen, sequence control means 57 includes a timer motor 59 which, in a conventional sequence control means would comprise a synchronous electric motor due to its accuracy, but in the present application, for reasons to become evident as the description proceeds, may involve a less accurate electric motor. Timer motor 59 drives, through direct mechanical linkage, cams 60 and 61. Cam 60 controls the operation of switch 62 while cam 61 controls the operation of switch 63 in a manner well known in the appliance control art. A pressure sensitive fill switch 64 is electrically connected to switch 62 and valve 53. As can be seen in FIGURE 1, fill switch 64 is physically located to sense the pressure within the housing of pump 26. Fill switch 64 is a single pole double throw switch normally biased toward terminal 65 and is moved to terminal 66 as the pressure within pump housing exceeds some predetermined value. It should be realized that the pressure sensed by fill switch 64 may be a static pressure created by a predetermined level of fluid filling the housing 31 of pump 26, bottom 28, sump 22 and a portion of wash chamber 12 or it may be pressure created by operation of the impeller within pump 26 even though the static level of fluid has decreased below that necessary to operate the switch.

A level sensitive flood switch 67 is electrically connected to valve 53 and heating means 52. Again referring briefly to FIGURE 1, it can be seen that flood switch 67 is physically positioned ideally within wash chamber 12 to operate as the liquid level within wash chamber 12 exceeds a predetermined height. Flood switch 67 is biased to be normally closed against terminal 68, as illustrated in FIGURE 4, and closes against terminal 69 as the liquid level within wash chamber 12 reaches, or exceeds, a predetermined height. This predetermined height is at the highest allowable level which will avoid leakage of wash fluid from wash chamber 12 through any vents or other openings which may be provided in cabinet 11 or door 15.

Since the electrical connections among the various components of the control system schematically represented in FIGURE 4 can be best appreciated from a study of FIGURE 4, a detailed element by element verbal description of the connections will not be given here.

A description of the operation of the control system of FIGURE 4 will now be given as it relates to a complete operational cycle of dishwasher 10. Power lines L₁ and L₂ are connected across a conventional source of 110 volt, 60 cycle AC power. A master switch 70 is adapted to be closed as the latching means (not shown) for door 15 is operated to secure door 15 in the closed position. Thus, switch 70 serves to de-energize the control system at any time door 15 is not secured in its closed position to prevent the inadvertent escape of wash fluid from wash chamber 12. Once door 15 has been secured in the closed position, knob 58 is manipulated to initiate operation of dishwasher 10 by rotation thereof a few degrees which rotates cam 60 to close switch 62. As switch 62 is closed, valve 53 is energized to begin the admission of water to the wash chamber 12 since fill switch 64 is closed against terminal 65 due to the absence of water pressure in pump 26 and flood switch 67 is closed against terminal 68 due to the absence of sufficiently high liquid level within wash chamber 12. Valve 53 is energized by the flow of current therethrough which also passes through heating means 52. Heating means 52 may be of the conventional electrical resistance type which is of low impedance. A heating means of the size illustrated in FIGURE 1 and normally used in dishwasher of the type shown, would have an impedance of 15 to 20 ohms. The control system would remain in this condition, i.e., valve 53 in the open position allowing water to enter wash chamber 12, until the level of water reached a height wherein the pressure at switch 64 exceeded the predetermined level, which corresponds to a normal charge of water. At this point, switch 64 would open from terminal 65 and close on terminal 66 thus de-energizing valve 53 and terminating the admission of water to wash chamber 12.

As switch 64 closes against terminal 66, timer motor 59 is energized through flood switch 67 and heating means 52 to drive cams 60 and 61. Motor 27 is also energized, in parallel with timer motor 59, to drive pump 26 and propel the fluid up through spray device 24 to effectuate the first rinse of the articles contained therein. As the fluid is pumped up through spray device 24, the static level decreases; however, operation of pump 26 builds up a sustaining pressure on fill switch 64 to keep it closed on terminal 66 even though the static level decreases below that necessary to keep switch 64 closed on terminal 66.

Referring now to FIGURE 5, the action of switches 62 and 63, due to the configurations of cams 60 and 61 respectively, is illustrated. Thus, it can be seen after a few minutes, specifically the duration of the first pre-rinse, cam 61 closes switch 63 on terminal 71. This energizes solenoid 40 to move valve element 50 toward sealing engagement with outlet 33. As discussed above, the fluid pressure within the housing 31 moves valve element into complete sealing engagement with outlet 33 and opens outlet 34. Thus, pump 26 will effectuate

draining of the fluid from the dishwasher. This condition will obtain until substantially all the fluid has been drained from the dishwasher at which time fill switch 64 will again close on terminal 65 thus de-energizing solenoid 40, timer motor 59 and motor 27. As motor 27 is de-energized, spring 51a will rotate arm 49 to bring valve element 51 into sealing engagement with outlet 34 and will open outlet 33.

It should be noted at this time that because switch 64 senses the pressure within pump housing 31, it remains closed on terminal 66 until substantially all of the water has been pumped out through outlet 34 even though the static pressure created by the level of water in boot 28 and sump 22 is less than that required to maintain switch 64 closed against terminal 66 under static conditions. Thus, solenoid 40 and motor 27 remain energized until substantially all of the fluid has been pumped from the dishwasher.

It should be noted that switch 63 need be maintained in its closed position on terminal 71 for only a few seconds and may then be returned to its off position. Once the fluid pressure has established valve element 50 in sealing relationship with outlet 33, it is no longer necessary to maintain solenoid 40 energized. It is necessary to de-energize solenoid 40 so that spring 51a will be free to move valve element 51 into sealing relationship with outlet 34 as soon as the pressure within pump 26 decreases as substantially all of the fluid is pumped out through outlet 34.

A review of FIGURE 5 will show that the foregoing described sequence of events may be repeated several times and, in the preferred form, would be performed a total of five times. The first two times would provide pre-rinses, the third time would provide an elongated wash wherein detergent is added to the water by means of a detergent dispenser (not shown), and the last two would provide post-rinses. Following the second post-rinse, cam 61 is configured to move switch 63 into contact with terminal 72 to thus apply the full voltage L₁-L₂ across heating means 52. Since fill switch 64 will close on terminal 65 as the water is drained from pump housing 31, timer motor 59 will be energized by completion of a circuit through terminal 72 of switch 63, terminal 68 of flood switch 67 and the low impedance motor winding of motor 27. A shaded pole or induction motor of suitable power to drive pump 26 has an impedance of approximately 2 ohms. Thus, sufficient voltage will be dropped across timer motor 59 to cause it to run. Since the current through timer motor 59 is approximately 0.2 amp., the voltage across motor 27 is approximately 0.4 volt. Thus motor 27 does not run during this condition. Valve 53 will not be energized even though fill switch 64 is closed on terminal 65 and flood switch 67 is closed on terminal 68 because the circuit through terminal 72 of switch 63 shunts valve 53. This condition exists for several minutes and comprises the drying portion of the operational cycle with the heat generated by heating means 52 serving to facilitate drying of the articles supported by racks 13 and 14. Upon the termination of the predetermined length of time of the drying portion of the cycle, cam 60 opens switch 62 to de-energize the entire control system. Cam 61 returns switch 63 to its off position during manual turning of knob 58 at the beginning of a subsequent cycle.

Flood switch 67 remains closed on terminal 68 at all times during normal operation of a dishwasher 10 and closes upon terminal 69 only during that abnormal condition when excessive amounts of water, or other fluid, is present in wash chamber 12. Such abnormal condition may occur in the event that fill switch 64 fails to operate properly and continues to maintain valve 53 in its open position even though the required charge of water has been admitted to the dishwasher.

When an excessive amount of water operates flood switch 67 to close against terminal 69, due to a malfunc-

tion of switch 64, it can be seen that timer motor 59 and solenoid 40 will be energized along with motor 27, with current flowing through switch 64, valve 53, timer motor 59, and then through solenoid 40 and heater 52 in parallel with motor 27. Although a circuit is established through valve 53, the impedance of timer motor 59 is relatively high (approximately 800 ohms compared to 600 ohms for valve 53) leaving an insufficient voltage drop across valve 53 to cause opening thereof. When such a situation exists, the operator of the dishwasher will recognize the fact that a problem exists due to the fact that the cycle will not be completed. The dishwasher may be left in this condition until a serviceman arrives to repair the malfunctioning switch 64.

In the event that an excessive amount of water gains admission to wash chamber 12 even though switch 64 is operating properly, then switch 64 would be closed against terminal 66 and flood switch 67 would be closed against terminal 69. In this condition, timer motor 59 would not be energized; however, solenoid 40 would be energized through switch 67 and heater 52 while motor 27 would be energized also thus placing the control system in the drain position. Such a situation could occur if valve 53 experienced a mechanical malfunction wherein it was stuck in the open position and remained in that position even though the electrical energy thereof was terminated. Because the capacity of pump 26 greatly exceeds that of valve 53, escape of fluid from dishwasher 10 would be prevented as long as solenoid 40 and motor 27 remained energized. Since most dishwashers are provided with a manually operable valve in series with valve 53, the operator of the dishwasher could close the manual valve to shut off the supply of water to the dishwasher until a serviceman arrived to correct the malfunction.

Referring now to FIGURE 6, a modification of the control system of FIGURE 4 is illustrated and involves, primarily, repositioning electrically of the flood switch to a location adjacent master switch 70. In FIGURE 6, the flood switch is given the numeral 67a and its contacts are given the numerals 68a and 69a. Similarly, the fill switch is given a numeral 64a and its terminals are given the numerals 65a and 66a. The remaining elements of the control system carry the same numerals as those in FIGURE 4 since they may be substantially identical thereto. The system of FIGURE 6 operates substantially the same as the system of FIGURE 4 as long as the liquid level within wash chamber 12 does not reach a height sufficient to cause flood switch 67a to close upon terminal 69a. Flood switch 67a normally remains closed on the terminal 68a. Fill switch 64a remains closed on terminal 65a until switch 64a senses a pressure in pump 26 of a predetermined level whereupon switch 64a closes on terminal 66a. When switch 64a closes on terminal 66a, it can be seen that timer motor 59 will be energized through heating means 52 and motor 27 will also be energized with solenoid 40 remaining de-energized until switch 63 is closed upon terminal 71 by cam 61 as in the system of FIGURE 4. When switch 63 closes on terminal 71, solenoid 40 will effectuate draining of the fluid from the dishwasher and, as all the fluid drains therefrom, switch 64a will again close on terminal 65a to initiate a repetition of the sequence of events.

The drying portion of the cycle finds flood switch 67a closed on terminal 68a and fill switch 64a closed on terminal 65a. Heating means 52 is energized through terminal 72 of switch 63. Timer motor 59 is energized through terminal 72 of switch 63 and then in parallel to heater 52 through the low impedance winding of motor 27. Switch 63 shunts valve 53 to prevent admission of water to wash chamber 12.

The operation of the flood switch 67a is such that when it closes on terminal 69a, valve 53 is de-energized, despite the setting of switch 64a, and timer motor 59 and motor 27 are energized. Thus, in the event of a mal-

function of fill switch 64a, valve 53 will de-energized to terminate admission of water to wash chamber 12 and no additional water may be admitted until the level within wash chamber 12 has decreased to the extent that flood switch 67a closes on terminal 68a. The level will be lowered through the normal operation of sequence control means 57 wherein cam 61 will cause switch 63 to eventually close on terminal 71 thus energizing solenoid 40 to drain wash chamber 12. The arrangement of FIGURE 6 may prove to be advantageous over that of FIGURE 4 in the event that a "trickle" leak in valve 53 is established. This is a sort of leak which may occur if a small grain of sand lodges between the valve and the valve seat thus allowing a very slight trickle of water to pass through valve 53 even though it is de-energized. If this occurs, and master switch 70 is closed, flood switch 67a will energize the system, as described above, even though sequence control means 57 has not been manually energized by knob 58. Such a situation could occur, for example, when a home owner leaves on vacation for several weeks during which period of time the trickle of water may accumulate sufficient water within wash chamber 12 to create an overflow condition. The home owner need only secure door 15 to close switch 70 to create a pump out or drainage of dishwasher 10 as the accumulation of water therein reaches the overflow stage.

Thus, the aforescribed invention provides an improved control system for an automatic dishwasher which is greatly simplified due to the fact that only two timer operated switches are involved. A positive measured fill of each charge of dishwasher is provided, flood protection is provided and the main motor, such as motor 27, is de-energized as soon as substantially all the water has been drained from the dishwasher thus reducing the amount of noise generated by the dishwasher during an operational cycle thereof. Moreover, the positive measured fill and the employment of a pressure sensitive fill switch to control draining allows the use of a less accurate, and thus less expensive, timer motor since the only operation which require accurate timing in conventional control systems, fill and drain, are not subject, in the present control system, to the accuracy of the sequence control means.

What I claim as new and desire to secure by Letters Patent of the United States is:

1. In an automatic dishwasher having a wash chamber, a pump having a housing, a pump motor to drive said pump, an electrically-operated outlet valve to control the flow from said pump and having a drain position, and an electrically-operated water valve to admit water to said wash chamber, a control system comprising:
  - (a) a pressure sensitive fill switch having first and second operative positions and located to sense the pressure within said pump housing,
  - (b) said fill switch being held in said second position when the pressure within said pump housing exceeds a predetermined level,
  - (c) a sequence control means including a timer motor and at least one switch having at least one closed position and operated in predetermined sequence by said timer motor,
  - (d) said water valve being electrically connected to said fill switch to be energized when said fill switch is in said first operative position,
  - (e) said timer motor and said pump motor being electrically connected to said fill switch to be energized when said fill switch is in said second operative position,
  - (f) said outlet valve being electrically connected to said fill switch and to said switch in said sequence control means whereby said outlet valve is moved toward said drain position when said fill switch is in said second operative position and said switch in said sequence control means is in said closed position.
2. The invention of claim 1 further comprising a level sensitive flood switch positioned to operate as the liquid

level within said wash chamber exceeds a predetermined height, said flood switch being in electrical series circuit with said water valve to over-ride said fill switch and de-energize said water valve whenever said liquid level exceeds said predetermined height.

3. The invention of claim 1 further comprising an electrical heating element to facilitate drying of articles within said wash chamber and said switch in said sequence control means has a second closed position to energize said heating element during a predetermined timed interval.

4. The invention of claim 1 further comprising a level sensitive flood switch having first and second operative positions and located to move to said second operative position as the liquid level within said wash chamber exceeds a predetermined height, said flood switch when in said first operative position allowing energization of said water valve but when in said second operative position energizing said sequence control means and energizing said pump motor while preventing energization of said water valve.

5. In an automatic dishwasher having a wash chamber, a pump having a housing, a pump motor to drive said pump, an electrically-operated outlet valve to control the flow from said pump and having a drain position, and an electrically-operated water valve to admit water to said wash chamber, a control system comprising:

- (a) a sequence control means having a timer motor and at least one timer switch controlled by said timer motor,
- (b) a fill switch having first and second terminals,
- (c) said fill switch being normally closed on said first terminal and being sensitive to the pressure within said pump housing to open said fill switch from said first terminal and close it on said second terminal when said pressure exceeds a predetermined level,
- (d) said first terminal being electrically connected to said water valve,
- (e) said second terminal being electrically connected to said timer motor, said outlet valve, and said pump motor,
- (f) said timer switch being electrically connected to said outlet valve in electrical series circuit with said second terminal whereby said outlet valve is energized and moved toward said drain position when said timer switch is closed and said fill switch is closed on said second terminal.

5. The invention of claim 5 wherein said fill switch de-energizes said outlet valve, said timer motor and said pump motor and energizes said water valve as the pressure within said pump housing decreases sufficiently to open said fill switch from said second terminal and close it on said first terminal.

10. The invention of claim 5 further comprising a flood switch having at least one terminal electrically connected to said outlet valve in electrical parallel circuit with said timer switch whereby said outlet valve is energized and moved toward said drain position when said flood switch is closed on said one terminal even though said timer switch may be open, said flood switch being sensitive to the level of liquid within said wash chamber to close on said one terminal when said level exceeds a predetermined height.

15. The invention of claim 7 wherein said flood switch has a second terminal electrically connected to said water valve in electrical series circuit with said fill switch whereby said water valve is de-energized as said flood switch opens said second terminal and closes on said one terminal.

20. The invention of claim 5 further comprising a flood switch having a first terminal and a second terminal, said second terminal being connected in electrical series circuit with said fill switch and said first terminal being electrically connected to said timer motor, said pump motor and said timer switch, said flood switch being positioned to sense when the level of liquid within said wash chamber exceeds a predetermined level, said flood switch being adapted to open from said second terminal and close on said first terminal as said level exceeds said predetermined height whereby said water valve is de-energized and said timer motor and said pump are energized and said outlet valve will become energized upon closing of said timer switch.
